COMBINE

Robert L. Malcolm and Darwin C. Bichel, East Moline, Ill., and Henry Dreyfuss and James M. Conner, South Pasadena, Calif., assignors to Deere & Company, Moline, Ill., a corporation of Delaware

Filed Sept. 10, 1968, Ser. No. 13,474

Term of patent 14 years

Int. Cl. D15—03

U.S. Cl. D40—1

FIG. 1

FIG. 2

FIG. 3

FIG. 4

FIG. 1 is an upper left front perspective view of a combine embodying our new design.

FIG. 2 is a right side perspective view of the combine.

FIG. 3 is a left side perspective view of the combine.

FIG. 4 is a front perspective view of the combine.

The dominant features of our design reside in the solid line portions of the drawings.

We claim:

The ornamental design for a combine, substantially as shown and described.
